(57) **CLAIM**

The ornamental design for an absorbent article package, as shown and described.

DESCRIPTION

The file of this patent contains at least one drawing executed in color. Copies of this patent with color drawings will be provided by the Office upon request and payment of the necessary fee.

FIG. 1 is a perspective front view of an absorbent article package embodying the new design;

FIG. 2 is a front view of the design shown in FIG. 1;
FIG. 3 is a right side view of the design shown in FIG. 1; the left side and back views are the same and thus omitted; and, FIG. 4 is a top view of the design shown in FIG. 1; the bottom view is the same and is thus omitted.

Broken lines shown in the figures described above depict environmental subject matter only and form no part of the claimed design.

**1 Claim, 4 Drawing Sheets
(2 of 4 Drawing Sheet(s) Filed in Color)**
